BUTTON MAKING MACHINE

Application filed June 1, 1929. Serial No. 367,760.

This invention relates to button making machines, and more particularly to a machine by which buttons may be made from rods of suitable material, such as a casein product.

Heretofore, in the manufacture of buttons, it has been customary to first cut the material from which the buttons are made into discs or blanks of the proper size. 10 These blanks are placed, usually by hand, into chucks of the button making machine, after which they are shaped and grooved as may be desired.

It will be noted that there are apparently 15 a number of unnecessary steps in this method of making buttons, such as the preliminary forming of the button material into discs or blanks, and then feeding such discs or blanks to the button making machine.

20 It has been found that very satisfactory buttons may be made from certain casein products, which products are adapted to be formed into rods of any desired length.

It is an object of this invention to provide 25 a machine by which buttons may be formed from rods of material, such as a casein product, without necessitating preliminary forming of the material into discs or blanks, and also eliminate the necessity of feeding such blanks to a button making machine.

A further object of the invention is the 30 provision of a machine by which buttons may be made from a rod of material such as a casein product, without requiring the services of an attendant, the buttons being formed and the material fed to the machine automatically.

35 A further object is in the provision of a device in a button making machine whereby a facing tool may be periodically fed forwardly and brought into contact with an abrasive to maintain a sharp edge on said tool.

40 These and other advantages, which will later appear, are accomplished by the simple and practical construction and arrangement of parts hereinafter described and exhibited in the accompanying drawings, 45 forming part hereof, and in which:

Figure 1 represents a side elevation of the button making machine.

Figure 2 represents an elevational view of the other side of the machine.

Figure 3 represents a sectional view taken 55 on line 3-3 of Figure 1.

Figure 4 represents a rear elevation of the machine.

Figure 5 is an enlarged sectional view of 60 the tool feeding mechanism.

Figure 6 represents a plan view of the tool feeding mechanism.

Figure 7 represents a sectional view, enlarged, of the work feeding device.

Figures 8, 9 and 10 show the sequence of 65 steps in forming a button by my machine.

Referring to the drawings, in Figure 1, the machine is shown to have a base 1, with an upstanding main support 2. Journalled 70 in bearings 3 and 4 on the base, is a shaft 5, adapted to be driven by a belt 6. The shaft carries a worm 7 in mesh with a worm wheel 8, the latter being fixed to a shaft 9, which is journalled in a bearing 10 integral with the main support 2 and having also fixed 75 thereto the cam discs 11, 12, 13, 14, and 15.

The cam disc 12 is engaged by a rocker 16 pivoted on a shaft 17 journalled in a bearing on support 2, the rocker having an apertured arm 18 through which passes a pin 19 80 having a flange 20 adapted to be engaged by arm 18 when the latter is moved forwardly as shown in Figure 1. The pin 19 is connected with a bell crank 21 rotatably mounted in a bracket 22 on the support 2.

The arm 23 of the bell crank passes 85 through an aperture in a block 24 integral with a rod 25, the latter being guided vertically by the bracket extensions 26 and 27, and normally urged downwardly by a compression spring 28 bearing against the block 24 and the guide 26. The lower end of rod 25 is provided with an integral block 29 in which is journalled a rotatable member 30' and which, at predetermined times, comes 90 into the path of the rod of casein material 30 to limit the forward movement of the latter when it is released so that it may be forced forward by the action of the weight 95 31 which constantly urges the rod 30 in that 100

direction. The weight 31 is connected to a cord 32 which passes over a pulley 33, the cord being connected to a member 34, which slides in a groove and bears against the rear end of rod 30.

Cam 11 is engaged by the bell crank 35 pivoted to the support 2 at 36, the bell crank 35 having an arm 37 pivoted to a link 38, the latter being connected to arm 39 of a bell crank fixed to shaft 40, which is rotatably mounted in bearing 41 mounted on the support 2. The other arm 42 of the bell crank is offset and has mounted thereon a cutting tool 43 for rounding the edges of buttons.

15 The tool 43 is constantly urged towards an operative position by a tension spring 44 fixed to the bracket 27 and the arm 39.

The cam 14 is engaged by the arm 45 of a bell crank pivoted at 46 to the support 2.

20 The arm 47 of the bell crank is pivotally connected at 48 to a link 49, which in turn is pivotally connected to arm 50 fixed to a shaft 51 journalled in a bracket 52 mounted on support 2.

25 Integral with arm 50 is a depending arm 53 which has at its lower end a bearing 54 in which is journalled a shaft 55, the latter having fixed thereto a circular saw 56 and pulley 57 by means of which the shaft may be driven by belt 58. The rod 49 is normally urged downward by the pull of a tension spring 59 attached to arm 47 and the base 1.

Cam 15 is engaged by arm 60 of a rocker pivoted at 61 to support 2, the other arm 62 of the rocker having journalled in its extremity a shaft 63, to which is fixed an arm 64 connected by a link 65 to the arm 66 of a rocker pivotally mounted at 67 to the support 2, the rocker having an arm 68 engaging cam 13.

45 The arm 62 has a projection 69 on which is rotatably mounted an abrasive wheel 70, the latter being driven by a belt 71. The abrasive wheel 70 is for the purpose of sharpening a facing tool 72 clamped in a holder 73 fixed to shaft 63.

The tool 72 consists of a flat strip of cutting metal and is held securely against the base 74 of the holder by means of a member 50 75 fixed at one end to a pin 76 projecting from shaft 63, and a clamp 77 embracing the base 74, holds member 75 tightly against the tool to prevent accidental slipping of the latter.

55 After each facing operation the tool 72 is fed forwardly and then tilted into engagement with the abrasive wheel 70 so that the edge of the tool 72 is maintained sharp. The tool is intermittently fed forward by means 60 of a lug 78 engaging its rear end. (See Figures 5 and 6.)

The lug 78 is integral with an internally threaded block 79 mounted on a threaded shaft 80 having its ends journalled in the base 74. The lug 78 projects upwardly

through a slot 81 and rotary movement of the block 79 is prevented by the engagement of lug 78 with the sides of the slot. The tool 72 is guided in a groove 82 in the tool holder base.

70 Fixed to the shaft 80 is a worm wheel 83 in mesh with a worm 84, which is fixed to a shaft 85 journalled in the walls of the tool holder 73. The shaft 85 is journalled in a link 86 and has fixed thereto a ratchet 87, which cooperates with a pawl 88 to rotate shaft 85. The pawl 88 is pivoted to link 86 and is held in engagement with the ratchet by means of a spring 89 connecting the extremities of the pawl and the link 86. An arm 90 projects upwardly from the extremity of the arm 62, and is connected to the upper extremity of link 86 by means of a link 91. It will be seen that the portion of holder 73 between shafts 63 and 85, with link 91 constitute two sides of a parallelogram; the link 86 and the arm 90 constituting the other two sides. Since arm 90 is vertical and fixed, obviously changes in the angularity of link 91 and holder 73 will 90 cause slight rotary movements of their extremities. For example, when cam 13 causes counter clockwise rotation (see Figure 2) of arm 68, the tool holder 73 is moved upward to a horizontal and operative 95 position. During this movement the pawl 88 ratchets over the ratchet wheel 87. As the cam 13 continues to rotate and allows arm 68 to rotate clockwise, the spring 92, fixed to holder 73 and the base 1, pulls the 100 holder 73 downward so that the tool engages the abrasive wheel 70.

During the downward movement, the change in angularity of the parallelogram causes a tooth of the ratchet wheel 87 to 105 bear against the pawl 88, and the resistance of the latter rotates the wheel 87 and the shaft 85, which in turn causes rotation of the threaded shaft 80 through the worms 84 and worm wheel 83. Rotation of threaded shaft 80 causes lug 78 to feed the cutting tool 72 forwardly into a position to be sharpened by the abrasive wheel 70.

Journalled in bearings 93 and 94 integral with the support 2 is a shaft 17 having 115 fixed to one end thereof a crank arm 96, which is positioned in the path of a lug 97 integral with or fixed to the cam disc 15. (See Figures 2 and 4). Also fixed to shaft 17 is a collar 98 having integral therewith 120 a yoke 99, the latter being adapted to engage a flange 100 integral with a clamping cylinder 101 rotatably mounted in the stationary casing 102, the pulley 103 being also integral with the cylinder 101 and rotating 125 therewith, the pulley being driven by a belt 104.

The cylinder 101 is provided with a second flange 105 to receive pressure from a compression spring 106 which also bears against 130

a thrust bearing 107 adjustably fixed to the casing 102 by means of set screws 108. The spring normally urges the cylinder 101, which has a tapered opening, into wedging engagement with the chuck 109 to cause the latter to tightly hold the rod 30 of casein material from which the buttons are made. When crank arm 96 is engaged by lug 97, the cylinder 101 is forced rearwardly against the pressure of spring 106, and the chuck is released to allow the rod 30 to be moved forwardly by the action of weight 31 and member 34.

In operation, the cam discs 11, 12, 13, 14 and 15 rotate counter-clockwise, i. e., in the direction of the arrow shown in Figure 2. The first movement of the machine in the formation of a button is the action of cam 12 on arm 16 to allow spring 28 to cause 20 the rod 25 to descend to place the block 29 in the path of the rod 30 to limit the forward movement thereof. Immediately thereafter the lug 97 passes from engagement with arm 96 and the spring 106 forces the cylinder 101 forward to cause the chuck 109 to tightly grip the rod 30.

Almost simultaneously, the cam 11 moves to a position to allow spring 44 to draw the edge-shaping tool 43 into engagement with 30 the rod to shape the under side and edges of the button as shown in Figure 8. While this is taking place, cam 12 has acted on arm 16 to cause rod 25 to be raised, and cam 13 has acted on rocker arm 68 to move the 35 facing tool 72 to a horizontal position and cam 15 rotates rocker arms 60 and 62 to move tool 72 into engagement with the end of rod 30, whereupon tool 72 performs the facing operation as shown in Figure 9.

During the facing operation, tool 43 is being moved away from the rod, and cam 14 acts upon arm 45 to allow spring 59 to cause the circular saw 56 to be brought into engagement with the rod to sever the now 45 completely formed button. (See Figure 10.)

During the sawing operation, tool holder 73 is being tilted downward to place the tool in engagement with the abrasive wheel 70, 50 and the tool is fed forward slightly by action of the mechanism connected with ratchet wheel 87 and pawl 88, and the sequence of movements is repeated for the next button.

It will be seen that the rod 30 is first released so that it may be forced forward, and block 29 is placed in the path of the rod at the proper time to limit the forward movement of the rod, then the bottom and edges of the button are formed, then the face of the button is formed, and finally it is severed by the circular saw.

Mounted on a shelf 204 is an electric motor 202 having an abrasive wheel 203 fixed to 65 the shaft thereof. From time to time the

cutting tool 43 may be rotated into engagement with the wheel 203 for sharpening purposes.

The foregoing disclosure is to be regarded as descriptive and illustrative only, and not 70 as restrictive or limitative of the invention, of which obviously an embodiment may be constructed including many modifications without departing from the general scope herein indicated and denoted in the appended claims. 75

Having thus described my invention, what I claim as new and desire to secure by Letters Patent, is:

1. In a machine for making buttons from a rod of suitable material, a support, a tool holder pivotally mounted on the support, a facing tool movably mounted in the tool holder, an abrasive wheel mounted on the support, spring means to periodically tilt 80 the tool holder to bring the tool into engagement with the abrasive wheel, cam controlled means to raise the tool holder to a position in alignment with the rod, and means to periodically move the support to bring 85 the tool into engagement with the rod from which the buttons are made.

2. In a machine for making buttons from a rod of suitable material, a support, a tool holder pivotally mounted on the support, a tool movably mounted in the tool holder, a threaded shaft journaled in the tool holder, an internally threaded block mounted on the shaft, a lug integral with the block engaging the rear of the tool, means to prevent rotary movement of said block, a worm wheel fixed to said threaded shaft, a worm in engagement with said worm wheel, a shaft upon which said worm is fixed, a ratchet wheel fixed to said shaft, an arm in which said shaft is journaled, a projection from said support, a link connecting the upper end of said arm and said projection, the link and tool holder forming two sides of a parallelogram while the projection and 95 arm form the other two sides, a pawl mounted on said arm and engaging the ratchet wheel, and means to periodically tilt 100 the tool holder whereby the change of angularity of the parallelogram will cause the 105 pawl to rotate the ratchet wheel to cause the intermediate mechanism to move the tool forwardly in the tool holder. 110

3. In a device for automatically feeding a tool, a support, a tool holder pivotally 120 mounted on the support, a tool movably mounted in the tool holder, a shaft, means controlled by the rotation of the shaft to move the tool in the holder, a ratchet wheel fixed to said shaft, an arm in which said 125 shaft is journaled, a projection from said support, a link connecting the upper end of said arm and said projection, the link and tool holder forming two sides of a parallelogram while the projection and arm form 130

the other two sides, a pawl mounted on said arm and engaging the ratchet wheel, and means to periodically tilt the tool holder whereby the change of angularity of the parallelogram will cause the pawl to rotate 5 the ratchet wheel to cause the intermediate mechanism to move the tool forwardly in the tool holder.

4. In a device for automatically feeding 10 a tool, a support, a tool holder pivotally mounted on the support, a tool movably mounted in the tool holder, a shaft; means controlled by the rotation of the shaft to move the tool in the holder, an arm in which said shaft is journaled, a projection from 15 said support, a link connecting the upper end of said arm and the projection, the link and tool holder forming two sides of a parallelogram while the projection and arm form the other two sides, means to periodically tilt the tool holder, and engageable 20 means associated with the arm and shaft whereby the change in angularity of the parallelogram due to the tilting of the tool holder will cause the shaft to rotate to 25 cause the tool to move forwardly in the tool holder.

This specification signed this 29th day of May, 1929.

EMANUEL CLEMENS.
